CLAIM

The ornamental design for a battery pack as shown and described.

DESCRIPTION

FIG. 1 is a left front top perspective view of a first embodiment of a battery pack according to our new design.

FIG. 2 is a front view thereof.

FIG. 3 is a back view thereof.

FIG. 4 is a left-side view thereof.

FIG. 5 is a right-side view thereof.

FIG. 6 is a top view thereof.

FIG. 7 is a bottom view thereof.

FIG. 8 is a left front top perspective view according to a second embodiment of our new design.

FIG. 9 is a front view thereof.

FIG. 10 is a back view thereof.

FIG. 11 is a left-side view thereof.

FIG. 12 is a right-side view thereof.

FIG. 13 is a top view thereof; and,

FIG. 14 is a bottom view thereof.

The broken lines in the drawings illustrate portions of the battery pack that form no part of the claimed design.

1 Claim, 14 Drawing Sheets
